UNITED STATES PATENT OFFICE

149,432

DESIGN FOR A SPOON OR OTHER ARTICLE OF FLATWARE

Thomas B. McKiernan, Meriden, Conn., assignor to The Ellmore Silver Co., Inc., Meriden, Conn.,
a corporation of Connecticut

Application January 29, 1947, Serial No. 136,488

Term of patent 14 years

(Cl. D54—12)

To all whom it may concern:

Be it known that I, Thomas B. McKiernan, a citizen of the United States, residing in the city of Meriden, county of New Haven, and State of Connecticut, have invented a new, original, and ornamental Design for a Spoon or Other Article of Flatware, of which the following is a specification, reference being had to the accompanying drawing, forming a part thereof.

I claim:

The ornamental design for a spoon or other article of flatware, as shown and described.

THOMAS B. MCKIERNAN.
